UNITED STATES PATENT OFFICE.

GEORGES GRAUSS, OF PARIS, FRANCE.

CENTRIFUGAL DRYING APPARATUS.

Application filed March 7, 1924. Serial No. 697,643.

To all whom it may concern:

Be it known that I, GEORGES GRAUSS, a citizen of France, and a resident of Paris, France, have invented some new and useful 5 **Improvements in Centrifugal Drying Apparatus**, of which the following is a specification.

This invention relates to centrifugal drying apparatus and its object is to provide a 10 drying apparatus characterized by the application of mechanical means for utilizing the centrifugal force for the actuation of the basket, and to provide means to permit the basket to be readily removed for purposes of emptying or change, when the apparatus is at rest.

A drying apparatus together with the device in view is represented in the annexed drawings showing:

20 In Figure 1 a vertical section through the axis of the upper part of the apparatus, and

In Figure 2 a plan view, partly in section. The container *a*, the vertical shaft *c* 25 and its controlling means are the same as in the apparatus known.

The basket receiving the matter to be dried or to be turbined is composed of a member *g* of an appropriate form forming 30 the hub *g'*, a casing *g²*, which is of greater diameter than the hub, and also the bottom *g³* on which is fixed a circular shell *h* surmounting by a cap *i*. The member *g* is suspended from the upper portion of the vertical shaft *c* the hub *g'* being bored to receive said shaft and its upwardly extending spindle *c'*, the central portion of the hub bearing on a collar *e*, which collar bears on the shoulder *e'* of the shaft *c*.

40 For starting, the vertical shaft *c* is actuated by an electric motor, steam engine or the like, directly or indirectly by means of a belt, cable or the like.

The motion is transmitted to the basket 45 by means of a piece *k* with radial wings, fixed on the shaft *c*.

This piece *k* has an outer diameter such as to permit of its rotation within the casing *g²* and has compartments formed between vertical partitions *k'* the thickness of 50 which is reduced towards the axis. Movable segments *r* are arranged in the said compartments *c*. The segments *r* are provided

each with a frictional substance on the outer face *r'* and are, owing to the effect of the 55 centrifugal force, applied against the inner face of the casing *g²*, hence causing, by friction, the progressive actuation of the latter.

When the drying or revolving action is 60 finished braking is effected by the simultaneous contact of the braking shoes *j* with the hub *g*.

After release of the shoes *j* the basket 65 may be removed directly with aid of hooks *f* fixed at the upper part of the hub *g*. While the basket is being emptied another basket may be placed on the same machine which may be started immediately thereafter. After finishing the drying or turbining with 70 the second basket, the first one after emptying and changing will be ready for use.

These operations follow each other very rapidly owing to the absence of intermediate 75 handlings, the basket resting freely on the shaft *c*.

To the advantages of this device, the dimensions whereof are variable as well as the details of construction, may be added the facility of interchanging the baskets, the 80 particular disposition of each one of them permitting the use of the same drying apparatus for different kinds of work.

What I claim, is:—

1. A centrifugal drying apparatus comprising a fixed container, a vertical power shaft arranged in the container, and a basket in the container, said basket having a bottom member forming a casing and also forming a hub above the casing, the said shaft extending upwardly through the hub and having an upwardly extending spindle, a collar arranged in said hub, around the lower portion of said spindle and bearing on the shoulder formed by said shaft around the 95 base of said spindle and whereby said basket is suspended; centrifugally acting clutch mechanism in said casing to connect said basket to said shaft for rotation by the latter and means on the upper end of said hub 100 to facilitate the lifting of said basket from said shaft.

2. A centrifugal drying apparatus comprising a fixed container, a vertical power shaft arranged in the container, and a basket in the container, said basket having a 105

bottom member forming a casing and also basket is suspended; centrifugally acting clutch mechanism in said casing to connect said basket to said shaft for rotation by the latter and brake mechanism for said basket also arranged in said casing. ¹⁰

5 a collar arranged in said hub, around the lower portion of said spindle and bearing on the shoulder formed by said shaft around the base of said spindle and whereby said

In witness whereof I affix my signature.

GEORGES GRAUSS.
